UNITED STATES PATENT OFFICE.

ALEXANDER MILES, OF TOLEDO, OHIO.

IMPROVEMENT IN COMPOUNDS FOR CLEANSING THE HAIR.

Specification forming part of Letters Patent No. 121,536, dated December 5, 1871.

To all whom it may concern:

Be it known that I, ALEXANDER MILES, of Toledo, Ohio, have invented a certain Compound called Cleansing Balm, to be used in cleansing the hair and purifying the scalp.

The nature of the invention consists in mixing rain-water, borax, and pulverized French castile soap with a solution of salts of tartar, dissolved in hot rain-water.

To prepare the cleansing balm take one ounce borax, one pound pulverized French castile soap, and dissolve the same in three quarts and six gills of rain-water. Then take one-half pound salts of tartar dissolved in two gills hot rain-water. In mixing for use take ten ounces of the melted soap and borax; add to this one ounce of

oil of bergamot or any other kind of oil which is used to perfume; beat hard two or three minutes. Then take four and one-half ounces salts of tartar in solution, beat hard ten minutes; add glair of an egg; beat five minutes.

I claim as my invention—

The combination of borax, French castile soap, rain-water, and solution of salts of tartar with any appropriate perfume and the glair of an egg, substantially in the proportion named, and for the purpose described.

ALEX. MILES.
